FLASHLIGHT

Orville T. Wood, Clinton, Mass., assignor to Blake Manufacturing Corporation, Clinton, Mass., a corporation of Massachusetts

Original application May 20, 1938, Serial No. 209,034. Divided and this application December 22, 1938, Serial No. 247,191

4 Claims. (Cl. 240—10.6)

This invention relates to flashlights and more particularly to flashlights in which the casing is formed of a moldable material, such as a synthetic resinoid.

Many problems present themselves in the creation of a flashlight or electric hand lantern of moldable material since such flashlights must make use of the standard flashlight cells and other parts which are readily purchased in the open market for replacement. In every flashlight must be found a lens, a reflector, a miniature incandescent lamp, the dry cells aforesaid and some form of circuit closing device. The use of moldable material, such as a synthetic resinoid, is desirable for a variety of reasons. It is not conductive and hence may be used in working around electrical apparatus with no danger of creating a short circuit if the flashlight is inadvertently laid down upon a piece of the apparatus or if it is found necessary to place the flashlight in a position to throw the light upon the part being repaired or adjusted. A flashlight, if comprised of exposed metallic parts, might create a serious short circuit. Moreover, synthetic resinoids are now available in many colors and ornamental and pleasing effects may be obtained which have not heretofore been possible with the metallic, hard rubber or fiber cases heretofore used. The question of price, in an era of sharp competition, is also material and the molding of a unitary casing affords opportunities for a reduction in the cost of manufacture.

In the art of molding, however, the designer is restricted by reason of the necessity of adapting the shape of the article to molding practice and to the necessity of providing for the removal of the molded article from the mold. The requirement, therefore, of adapting a molded article to the usual tubular form of flashlight making use of common flashlight practice and utilizing standard parts, presents problems which this invention seeks to overcome. There is provided in accordance with the present invention a flashlight comprising a one piece molded body of tubular cross-section for use as a flashlight casing containing the standard type of flashlight dry cell. To facilitate molding a small hole or small passage is formed in the bottom of what would otherwise be the closed end in order to permit the anchoring of the outboard end of the core of the mold and thereby attain a more uniform thickness of the molded plastic casing wall.

The invention seeks a flashlight in which a spare lamp is carried in a molded flashlight casing. Accordingly, the end of the flashlight casing

provided with the passage is closed by an end closure member or plug adapted to be releasably retained within the opening and to support a spare lamp within the flashlight body. Conveniently, the closure or plug is retained in position by resilient latching means which may, if desired, be also utilized to support the spare lamp.

Another object of the invention is to provide the flashlight of this invention with a reflecting surface which may be used as a signal; for instance, with reflected light and to this end the end closure for the end of the casing remote from the lens may, if desired, comprise a colored reflecting button which not only has the utilitarian purpose of reflecting light, as will be understood, but adds an ornamental feature to the flashlight enhancing its appeal to the purchaser.

It is still another object of the invention to provide a molded flashlight casing of ornamental appearance having provision for carrying a spare lamp, and which is practical from the standpoint of ease and cheapness of manufacture and convenience and durability in use.

These and other objects of the invention and the means for their attainment will be more apparent from the following detailed description, taken in connection with the accompanying drawing illustrating various embodiments by which the invention may be realized, and in which:

Figure 1 is a view showing, in elevation, one form taken by a flashlight to which the invention may be applied, the lower portion of the casing being in section to show details of construction of the lower end whereby a spare lamp carrier may be used;

Figure 2 is a view showing another form taken by the spare lamp carrier of this invention; and

Fig. 3 is a fragmentary sectional view taken in the plane indicated by the line 3—3 of Figure 2 and looking in the direction of the arrows.

It will be obvious as the description proceeds that the invention is not limited to any particular moldable composition for the material of the casing nor to the specific shape of the flashlight casing.

This application is a division of my copending application, Serial No. 209,034, filing date May 20, 1938.

The flashlight casing of this invention may take the form of a generally elongated tubular casing 15 which is apertured at its lower end and open at its upper end, as viewed. While the casing may be of constant diameter, both from the

standpoint of molding and for the sake of appearance, it is desirable that the casing taper slightly, as at 17, toward the lower end which tapers, as at 18, more sharply to a blunt or rounded point 85 to present a smooth, unbroken surface.

The inner surface 25 is, conveniently, at its lower end so formed as to provide a shoulder 19 on which may seat the helical spring 28 which engages the bottom of the battery and urges it 10 toward the open upper end. This spring 28 conveniently serves as a portion of the electrical circuit connecting the outer zinc cup terminal 29 of the battery with a conductive strip 31 extending upwardly to the circuit closing instrumentality 32.

The lower end of the flashlight casing is formed with a bore 83 of reduced diameter as hereinbefore explained. This bore is adapted to be closed by a plug or closure member 84 serving 20 as a bottom closure member. The surface 85 of the closure member merges with the surface 18 of the casing. As shown, the closure member 84 is provided with an outwardly extending portion 86 overlapping the end surface 81.

25 The closure member 84 may be of any suitable material. It may be of a material such as colored glass or ruby colored reflecting or lens material whereby light from an exterior source may be reflected therefrom.

30 The closure member 84 may conveniently be removably retained on the end of the casing to close that open end, as by a plurality of spring fingers 89 secured in some convenient fashion as by a rivet or eyelet 90 embedded in the material 35 of the closure 84. The fingers 89 are shown as formed with an outwardly deflected portion 91 serving as detents or latch members which, when the material of the fingers 89 is of resilient material, snaps over the upwardly facing shoulder formed by the bottom surface 92 of the casing 40 to retain the closure member 84 in position.

Two or more such spring fingers may be provided which may conveniently be bent in substantially U-shape and secured at their midpoint 45 by the rivet 90. These latch members 89, 91 serve, conveniently, as retaining devices for a spare lamp 95 in which event the ends of the spring fingers may be formed with another reversely bent or a corrugated portion 93 adapted 50 to engage an outwardly extending surface portion of the lamp base, such as threads or a flange thereon, to hold the lamp against displacement. When it is necessary to replace a lamp, it is only necessary to remove the closure 84 which brings 55 with it the lamp 95, withdrawing it from the bore 83.

A similar end closure and spare lamp carrier is illustrated in Figures 2 and 3. In this instance the closure member 84 is supported by the latch 60 members 91. A metallic member 97 is bent at its periphery about the closure portion 86 and to this member are secured, as by a rivet 99, the spring fingers 89. Otherwise the parts of this spare lamp carrier are the same as that previously described and corresponding reference 65 characters are affixed thereto.

It will thus be seen that an opening desirably present in the casing due to requirements of manufacture is utilized as a spare lamp receiving space and the spare lamp carrier therefore serves to mask the opening.

Various modifications will occur to those skilled in the art in the composition, configuration and disposition of the component elements going to make up the invention as a whole as well as in the selection and/or combination of particular 10 features and no limitation is intended by the foregoing description or illustrations in the accompanying drawing except as indicated in the appended claims.

What is claimed is:

1. A flashlight comprising a moulded tubular casing having a tapering lower end terminating in a flat transverse surface, said end being formed with an opening, said apertured portion being of a diameter less than the internal diameter of the 20 casing to define an upwardly facing shoulder, an end closure for the opening, a plurality of longitudinally extending resilient arms secured to the end closure, said arms having reversely bent portions to engage the shoulder and other reversely 25 bent portions to engage a spare lamp.

2. A flashlight comprising a molded casing having a lower end terminating in an end surface, said casing being formed with a bore extending from end to end, said bore, inwardly 30 spaced from the lower end, being formed with upwardly facing shoulder means, an end closure for the open lower end, a plurality of resilient arms secured to the end closure and the free ends of which are adapted to enter the bore, said arms 35 having portions so disposed as to engage the shoulder means, respectively, to retain the enclosure in position and said arms comprising means to engage a spare lamp to support the lamp within the bore.

3. A flashlight comprising a casing having a lower end terminating in an end surface, said casing being formed with a bore proximate the lower end formed with upwardly facing shoulder means inwardly of the end thereof, an end closure 45 for the open lower end, a plurality of resilient arms secured to the end closure and adapted to enter the bore, said arms having portions to engage the shoulder means to retain the end closure in position and said arms comprising 50 means to support a spare lamp within the bore.

4. A flashlight comprising a casing having a surface formed with an opening, said casing being provided with a tubular portion therewithin in register with the opening, said tubular portion having upwardly facing shoulder means inwardly spaced from said opening, a closure for the opening, a plurality of resilient arms secured to the closure and adapted to enter the tubular portion, said arms having portions to engage the 60 shoulder means to retain the closure in position and said arms comprising means to support a spare lamp within the tubular portion.
